BY *Watson E. Coleman*
ATTORNEY.

UNITED STATES PATENT OFFICE.

WILLIAM ISIAH WHEELER, OF SCOTTVILLE, ILLINOIS.

TEMPLATE.

Application filed April 9, 1923. Serial No. 630,917.

To all whom it may concern:

Be it known that I, WILLIAM ISIAH WHEELER, a citizen of the United States, residing at Scottville, in the county of Ma- 5 coupin and State of Illinois, have invented certain new and useful Improvements in Templates, of which the following is a specification, reference being had to the accompanying drawings.

10 This invention relates to certain improvements in templates and has relation more particularly to a device of this general character especially designed and adapted for use in duplicating or replacing plow shares and it is an object of the invention to provide a novel and improved device which is 15 adapted to be fitted to an old share and which, when the new share is applied thereto maintains the same in proper position to facilitate the share being welded or otherwise secured in working position.

Another object of the invention is to provide a template which is adapted to hold a plow share in position to be secured to a plow assembly and in a manner whereby such securing can be effected by a torch or electric welder or kindred fusion process.

The invention consists in the details of construction and in the combination and arrangement of the several parts of my improved template whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in side elevation of a template constructed in accordance with an embodiment of my invention and assembled with respect to a share to be replaced or duplicated;

Figure 2 is a view in perspective of the structure as illustrated in Figure 1 looking at the opposite side thereof;

Figure 3 is a view in perspective of the improved template as illustrated in Figure 2, the associated share and mold board section being indicated by dotted lines;

Figure 4 is a fragmentary view partly in top plan and partly in section illustrating

in detail the connection of the bar of the template with the bar of the share; Figure 5 is a view in perspective illustrating my improved template in an assembly for assembling a new share;

Figure 6 is a view in perspective showing the point and bar of the share applied to the template;

Figure 7 is a view in perspective showing the parts of the share in assembled relation for welding.

My improved template as herein disclosed comprises an elongated bar B of a form somewhat similar to the ordinary land side bar of a plow. The forward end portion of the bar B is laterally offset as at 1 and lapping said offset portion 1 is an extension 2 carried by the tapering head member 3. The extension 2 is provided with a slot 4 disposed longitudinally thereof through which is directed the bolt 5 also disposed through the offset portion 1 and associated with said bolt 5 is a nut 6. The bolt 5 and coacting nut 6 provide means whereby the head member 3 may be maintained in adjusted position with respect to the bar B and which adjustment is permitted in a direction lengthwise of the bar B through the instrumentality of the slot 4.

The member 3 proper is provided with an opening 7 which, when the template is being applied registers with the conventional opening in the bar 8 of the share S to be duplicated, the member 3 lapping the inner face of the bar 8. After this adjustment has been effected a bolt 9 is engaged through said registering openings to maintain the desired assembly.

The bolt 5 hereinbefore referred to is also disposed through a vertically directed slot 95 10 produced in a member or plate 11 whereby the member or plate 11 may be caused to have proper contact with the lower mold board member M from below to a point immediately adjacent to the share, the upper 100 edge of said member or plate 11 being formed as at a to facilitate such engagement. The bolt 5 and the associated nut 6 provide means whereby the member or plate 11 will be effectively held in desired adjustment. It is also preferred that the offset portion 1 be provided with a longitudinally disposed slot 12 as indicated by broken lines in Figure 1 to permit the member or plate 11 to have desired movement toward or

from the inner or adjacent end of the bar 8 of the share S.

Secured to and extending upwardly from the inner end of the offset portion 1 of the bar B is a brace or upright member 14 having its upper end portion 15 properly shaped to have close contact from below with the lower mold board member M, and said portion 15 is provided with a longitudinally disposed slot 16 which extends across a longitudinally disposed slot 17 properly positioned upon the member M and disposed through said slots 16 and 17 is a bolt 18 having associated therewith a nut 19 herein disclosed as engaging from below the portion 15 of the upright member 14. The lower marginal portion of the member M is also provided with the longitudinally disposed slots 20. Disposed through each of the two forward slots 20 is a bolt 21 also directed through a longitudinally disposed slot 22 produced in a portion of an elongated member 23 and associated with the bolt 21 is a nut 24. The slots 20 and 22 permit requisite adjustment of each of the members 23 to bring the opening 25 in the outer or lower end portion thereof in register with a conventional opening in the upper marginal portion of the share S and through which registering openings are disposed in a conventional manner the bolts 26.

The rear slot 20 also has disposed therethrough a bolt 21 which is directed through a longitudinally disposed slot 27 in a member 23^a, said member 23^a in its outer or lower end portion thereof having an opening 25^a for register with one of the conventional openings in the upper marginal portion of the share S and through which registering openings a bolt 26 also registers. The member 23^a at its upper portion is provided with an angular extension or arm 28 which laps an arm 29. Thelapping portions of the arms 28 and 29 being connected by a bolt 30 disposed therethrough and having associated therewith a clamping nut 31, one of said arms as 29 has produced therein a longitudinally disposed slot 32 through which the bolt 30 is directed and whereby the relative adjustment of the arms 28 and 29 may be effected to assure the proper fitting of the member M with respect to the share S.

The outer end portion of the arm 29 is provided with a depending arm 33 which overlies the inner face of the bar B. The overlying portions of the arms 33 and the bar B are provided with the angularly related slots 34 through which is directed a bolt 35 having associated therewith a nut 36. The slots 34 provide means for effecting the further adjustment of the arms 28 and 29 as may be required.

My template as herein disclosed is particularly adapted for use in the duplicating of a share in accordance with the method par-

ticularly disclosed in my pending application Serial No. 628,282 filed March 28, 1923 and in practice my improved template is fitted to an old share to be duplicated as illustrated particularly in Figures 1 and 2 and which can be readily accomplished by loosening the various bolts and after the adjustment has been accomplished and particularly as relates to the head 3, the member or plate 11 and the member M, the required bolts are tightened to maintain such parts in fixed assembly. After this is done the share S is removed.

The bar B' of a point P as is particularly illustrated in Figures 6 and 7 is then applied to the head member 3, the particular positioning of said bar B' being assured by the register of the opening therein with the opening 7 in the head member 3. The holding bolt 9' is then tightened to maintain this assembly. After this the share S' proper is secured by the bolts 26' to the members 23 and 23^a with the upper marginal portion of said share S' in close contact with the under edge of the member M. By this arrangement it is assured that the bar B' and point P and the share S will be properly assembled and my improved template effectively maintains such parts in assembled relation whereby the same can be connected by electric torch welding or other fusion process whereby such assembly is materially cheapened and effected without the necessity of hammering. By fitting the share S' with the member M it will be assured that when the assembled share and point are applied to the plow proper the same will properly fit the plow structure.

The member M' is made of such dimensions to permit the template to be employed in connection with plow shares of different sizes.

From the foregoing description it is thought to be obvious that a template constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A template for assembling a plow share and its bar and point comprising a bar adapted to be secured to the bar of the share, a member carried by the template bar against which the share is fitted, and means for securing said member to the share.
2. A template of the class described com-

- prising a bar adapted to be secured to the bar of a plow share, and a member carried by the template bar to fit against the upper edge of the share.
5. 3. A template of the class described comprising a bar adapted to be secured to the bar of a plow share, a member carried by the template bar to fit against the upper edge of the share, and means for holding said member rigid after being fitted.
10. 4. A template of the class described comprising a bar adapted to be secured to the bar of a plow share, a member carried by the template bar to fit against the upper edge of the share, and an upstanding member carried by the forward portion of the template portion for contact with the member from below.
15. 5. A template of the class described comprising a bar adapted to be secured to the bar of a plow share, a member carried by the template bar to fit against the upper edge of the share, an upright member carried by the forward portion of the template bar, and means for attaching said upright member to the first named member.
20. 6. A template of the class described comprising a bar adapted to be secured to the bar of a plow share, a member carried by the template bar to fit against the upper edge of the share, and members carried by the first named member for connection with the share.
25. 7. A template of the class described comprising a bar adapted to be secured to the bar of a plow share, a member carried by the template bar to fit against the upper edge of the share, members carried by the first named member for connection with the share, and means for securing one of said last named members to the template bar.
8. A template of the class described comprising a bar having an opening in an end portion for register with an opening in the bar of a share, a holding member insertible through said registering openings, and a member carried by the template bar to fit against the upper edge of the share.

In testimony whereof I hereunto affix my signature.

WILLIAM ISIAH WHEELER.
